UNITED STATES PATENT OFFICE.

JOSEPH D. BELL, OF SAN FRANCISCO, CALIFORNIA.

TOY VEHICLE.

Application filed January 9, 1923. Serial No. 611,603.

To all whom it may concern:

Be it known that I, JOSEPH D. BELL, a citizen of the United States, and a resident of the city and county of San Francisco, State of California, have made a new and useful invention, to wit, Improvements in Toy Vehicles; and I do hereby declare the following to be a full, clear, concise, and exact description of the same.

10 This invention relates particularly to a child's toy vehicle of the velocipede type.

An object of the invention is to provide a foot propelled vehicle of which the seat will have a teetering action when the vehicle moves. A further object of the invention is to provide a vehicle which may be propelled by a rocking or teetering movement of the seat of the vehicle by the occupant of said seat moving back and forth.

20 A still further object of the invention is to provide a toy vehicle that will be superior in point of simplicity and inexpensiveness of construction, positiveness of operation, facility and convenience in use and general efficiency. Other objects and advantages will appear as this description progresses.

In this specification and the annexed drawings, the invention is illustrated in the form considered to be the best but it is to be understood that the invention is not limited to such form, because it may be embodied in other forms, and it is also to be understood that in and by the claims following the description it is desired to cover the invention in whatsoever form it may be embodied.

In the accompanying one sheet of drawings:

Fig. 1 is a side elevation of a vehicle constructed in accordance with my invention.

Fig. 2 is a front end elevation of Fig. 1.

Fig. 3 is a modified form of vehicle constructed in accordance with my invention.

In detail the construction illustrated in the drawings comprises a frame, formed of wood, metal, or other equivalent material, and in the present instance arranged with side members 1 and 2, bent together at 3, to form a steering post bearing, and at the opposite end flaring outwardly to provide spaced bearings for the axle 4. The axle 4 extends between the spaced ends of the frame 1 and 2, and on its opposite ends the wheels 5 and 6 are fixedly secured.

55 A steering post 7 is rotatably journaled in the front end 3 of said frame. The lower

end 8 of the steering post is forked to receive the traction wheel 9 fixed on the shaft 10, revolubly journaled in the extreme lower end of the said steering post 7. The ends 60 11 and 12 of the shaft 10 extend downwardly on both sides of the steering post and terminate in projections eccentric relative to the shaft axis, and to which foot pedals 13 may be secured. The shaft 10 is also provided 65 with a crank-throw 14 intermediate the eccentric foot pedal support and the shaft axis, for the purpose to be hereinafter explained in detail. The upper end of the steering post 7 is provided with a handle 15 70 thereon for the obvious purpose of facilitating manipulation of the said steering column.

A seat member 16, arranged over the frame, is, by means of the extensions 17 and 75 17', adapted to be pivotally secured at 18 and 18' to the opposite sides 1 and 2 of said frame. The forward end of the seat 16 is slotted to allow the steering post 7 being passed therethrough. Depending stirrup 80 brackets 19 are fixed on both sides of the front end of the seat member 16.

A pivot member 20 is swivelly connected to the underside of the seat 16, in vertical alignment with the axis of the steering column, 7, said pivot being connected by the link 21 to the crank-throw 14 on the propeller shaft 10 of the traction wheel 9.

Rotative movement of the traction wheel 9, imparted by the feet (of an occupant on the seat 16) to the pedals on said traction wheel will cause the vehicle to move in a forward or rearward direction according to the manner in which the said traction wheel is rotated. Movement of the traction 95 wheel in either direction through the interposed link 21 connected to the pivoted seat 16, would cause said seat 16 to teeter or tip relative to the frame. Thus the occupant will experience a sensation somewhat similar to that of riding a galloping horse, except that the motion will be much easier, gentler and better suited to the physical condition of a child.

While I deem it desirable to obtain movement of the vehicle by the velocipede construction, however, movement of the vehicle can be effected by the occupant placing the feet on the stirrup racks 19 and then moving the body to and from a substantially vertical 110 position, causing a consequent lowering and raising of the seat 16, and a rotation of the

traction wheel 9. It is obvious that the forward movement of the vehicle might also be obtained by the occupant seated on the vehicle by placing the feet on the ground, 5 and in that manner propelling it.

In the modified form of vehicle shown in Fig. 3, I provide an auxiliary crank shaft 22 on the lower end of the frame adjacent to the axle 4. The axle 4 would be provided 10 with a pinion 23 thereon, meshing with a pinion 24 on the crank shaft 22. The crank shaft 22 would be connected by a link 21' to the under side of the rear end of the seat 16, the seat being pivoted in the usual manner to the vehicle frame. Thus a tilting or 15 rocking movement applied to the seat 16 will cause a rotative effect to be applied through the crank shaft 22 and intermeshing gears 23 and 24, and thence to the axle 20 4, the axle having the wheels 5 and 6 fixedly secured thereon. The front traction wheel 9 is secured on the shaft 10 and journaled in the lower end of the steering post 7, said shaft having the propelling pedals 25 13 thereon, by which a velocipede operation of the vehicle is produced. Thus, if the occupant of the vehicle on the seat 16 propels the vehicle with the feet applied to either the 30 pedals on the traction wheel, or by placing the feet in the seat stirrups 19, and rocking the body, or by placing the feet on the ground, a teetering movement is initiated to the seat 16, simulating the rising and falling movement produced on the rider of a 35 galloping horse.

A certain amount of jar and vibration is transmitted through the vehicle frame to the seat thereon, and thence to the spine of the vehicle's occupant. I have found that 40 the vehicle can be made much easier riding, and have all harmful effects eliminated by providing a cushion spring seat on the body member 16. The cushion seat would consist of a pair of non-resilient members held 45 apart by the resilient springs 26 and the assembly suitably covered with upholstering, or the like.

Having thus described this invention, what I claim and desire to secure by Letters 50 Patent is:

1. A toy vehicle including a frame; a seat pivotally secured to said frame; wheels

rotatably journaled on said frame; a steering post pivoted to an end of said frame; a wheel, revolvably mounted on a shaft journaled in the lower end of said steering post, said shaft having propeller pedals thereon; and a link on said seat swivelly connected to said shaft between one of the pedals and steering post for teetering said seat when 60 said wheel is rotated.

2. A toy vehicle including a frame; a seat pivotally secured to said frame; wheels rotatably journaled on said frame; a steering post pivoted to an end of said frame; a 65 shaft, having propeller pedals thereon, journaled in the lower end of said steering post; a traction wheel fixedly mounted on said shaft, and a link, connected at one end to said pivoted seat and at its opposite end 70 to said propeller pedal shaft.

3. A toy vehicle including a frame; a seat pivotally secured to said frame; wheels rotatably journaled on said frame; a steering post pivoted to an end of said frame; a 75 shaft, revolvably journaled in the lower end of said steering post, having a crank throw thereon; propeller pedals arranged on the ends of said shaft; a wheel fixedly mounted on said shaft adapted to be rotated by said 80 pedals; and a link connected to said pivoted seat and connected to said shaft throw for teetering said seat when said wheels are rotated.

4. A toy vehicle including a frame; a seat pivotally secured to said frame; wheels rotatably journaled on said frame; a steering post pivoted to an end of said frame; a shaft, revolvably journaled in the lower end of said steering post, having a crank throw 90 thereon; propeller pedals arranged on the ends of said shaft; a wheel fixedly mounted on said shaft adapted to be rotated by said 95 pedals; and a link swivelly connected to said pivoted seat and connected to said shaft throw for teetering said seat when said wheels are rotated.

In testimony whereof, I have hereunto set my hand at San Francisco, California, this 29th day of December, 1922.

JOSEPH D. BELL.

In presence of—
LINCOLN JOHNSON.
